(57) **CLAIM**

The ornamental design for a lipstick bullet, substantially as shown and described.

DESCRIPTION

FIG. 1 is a top, front and left side perspective view of our new design for a lipstick bullet;

FIG. 2 is a front elevation view of the lipstick bullet shown in FIG. 1;

FIG. 3 is a right side elevation view of the lipstick bullet shown in FIG. 1, a left side elevation view of the lipstick bullet being a mirror image thereof;

FIG. 4 is a top plan view of the lipstick bullet shown in FIG. 1;

FIG. 5 is a rear elevation view of the lipstick bullet shown in FIG. 1; and,

FIG. 6 is a bottom plan view of the lipstick bullet shown in FIG. 1.

The broken lines showing a cup shaped support base illustrate environmental structure that forms no part of the claimed design.
